W. A. GAUGH

GAS METER MECHANISM

Filed Oct. 28. 1924

FIG. I.

Patented May 17, 1927.

UNITED STATES PATENT OFFICE.

WILFORD A. GAUGH, OF ERIE, PENNSYLVANIA, ASSIGNOR TO AMERICAN METER COMPANY, OF PHILADELPHIA, PENNSYLVANIA, A CORPORATION OF DELAWARE.

GAS-METER MECHANISM.

Application filed October 28, 1924. Serial No. 746,345.

My invention relates to meters arranged to be operated by the pressure of gas to rotate the driving shaft of a dial registering mechanism. Ordinarily, the pressure of gas at the inlet of the meter is greater than the pressure of gas at the outlet. However, changes in temperature and other conditions sometimes raise the pressure of gas at the meter outlet higher than at said inlet which, of course, tends to reverse the operation of the meter mechanism and run the dial mechanism backwardly and thus reduce the previous registration of gas consumed. Moreover, unless means are provided to prevent or limit such reverse movement; the consumer may intentionally reduce the registration by reversing the connections of the meter and running it backwardly. It has been found in practice that if the meter is provided with means to positively prevent any reverse movement thereof the mechanism is liable to be broken at the weakest portion thereof by the strains incident to the reversal of pressure which may be occasioned by accidental conditions, as above contemplated. Therefore, it has been found necessary to provide such meters with means for permitting reverse movement of the meter mechanism to a limited extent sufficient to relieve the abnormal accidental reverse pressure. My present invention relates to a stop device for limiting such reverse movement.

As hereinafter described, my invention includes two levers constructed and arranged to be formed of pressed sheet metal with their fulcrums in coaxial relation; one of said levers being a stop lever which is normally in inoperative position, and the other of said levers being a trip lever which normally projects in the path of the radial "tangent arm" of the meter crank mechanism so as to be idly tripped by the latter at each revolution thereof without movement of said stop lever; but arranged to be tilted in the reverse direction by the reverse rotation of said tangent arm incident to the reverse movement of the meter mechanism, to then engage and set up the stop lever in position to stop the reverse rotation of the tangent arm and the meter mechanism connected therewith after more than one complete reverse revolution of said tangent arm.

My invention includes the various novel features of construction and arrangement hereinafter more definitely specified.

In said drawings; Fig. I is a plan view of a meter with the top wall thereof removed to show a plan view of a convenient embodiment of my invention.

Fig. II is a fragmentary vertical sectional view of said meter, taken on the line II, II in Fig. I.

Fig. III is an elevation of the right hand side of my improved stop mechanism as shown in Figs. I and II; the trip lever and stop lever being in the normal position.

Fig. IV is an elevation of said stop mechanism, similar to Fig. III, but showing the trip lever being idly tripped by the normal movement of the tangent arm in the direction of the arrow marked thereon.

Fig. V is an elevation of said stop mechanism similar to Fig. IV, but showing the trip lever being tripped by reverse movement of said tangent arm, indicated by the arrow marked thereon, to set up the stop lever to its operative position.

Fig. VI is an elevation of said stop mechanism, similar to Fig. V, but showing the stop lever in position to prevent further reverse movement of the tangent arm in the direction of the arrow marked thereon.

Fig. VII is a side elevation of said stop lever, detached.

Fig. VIII is a plan view of said stop lever, detached.

Fig. IX is a plan view of the trip lever, detached.

Referring to Figs. I and II; the meter casing 1 is provided with the inlet 2 and the outlet 3 communicating with the bellows chambers 4 and 5 beneath the horizontal partition 6 which is permanently secured in said meter casing 1 and forms the floor of the crank compartment 8 which contains the adjustable registering mechanism hereinafter described. The valve compartment 9 is formed within said crank compartment 8 by the sheet metal walls 10 which are permanently secured in said casing. The gas inlet 2 is in communication with the conduit 12 which is permanently connected with said partition 6 and directs the incoming gas into said valve compartment 9 from which it is distributed alternately to the bellows in the respective chambers 4 and 5 through ports controlled by suitable valves respectively operated by links 14 and 15 which are operatively engaged by the crank 16 on the crank shaft 17.

Said crank shaft 17 is journaled in the bracket 18 which is rigidly connected with the upper wall 10 of compartment 9, and said shaft 17 extends through the stuffing box 20 which is supported by said wall 10 and prevents escape of gas from said valve compartment 9 into said compartment 8.

The rock shafts 23 and 24 are adapted to be rocked by the movement of the bellows in said chambers 4 and 5 which are alternately expanded and collapsed by the pressure of gas inside and outside of said bellows. Said rock shafts 23 and 24 have respective lever arms 25 and 26 rigidly connected therewith, in such relation that the rocking movement of said shafts 23 and 24 under the operation of said bellows, causes said arms to oscillate from one extreme position to the other, respectively indicated by dash and dot lines and dash lines in Fig. I. Said rock lever arms 25 and 26 are respectively pivotally connected to links 27 and 28 which are both pivotally connected to the crank stud 30 shown in Figs. I and II. Said stud is mounted upon the crank "tangent" arm 31 which is flattened at its upper and lower surfaces, so that said stud cannot turn thereon, but said arm is screw threaded at its opposite edges to engage the nuts 34 and 35 upon respectively radially opposite sides of said stud 30 so that the latter may be adjusted toward and away from the axis of said crank shaft 17.

It is the object and effect of said bellows lever and link mechanism to rotate said crank shaft 17 in definite relation to the volume of gas dispensed through the meter, and effect registration thereof.

Said crank shaft 17 carries and drives the worm 37 which engages the worm gear 38 on the register shaft 39. Said shaft 39 is journaled in the stationary bracket 40 and in the frame 41; and the latter encloses the ordinary registering mechanism comprising a train of gears of ordinary construction and which is so arranged as to rotate a series of radial index pointers 42, 43, etc., in conjunction with dials upon the plate 45, to indicate the volume of gas dispensed.

It is intended that said shaft 39 shall rotate in the direction indicated by the arrow marked thereon in Fig. I, and the object of my improved stop mechanism is to prevent its reverse rotation except to the limited extent above contemplated. For that purpose, I provide said bracket 18 with two slots 47 and 48, in parallel relation near the outer end thereof, and extend a single fulcrum pin 50, in said bracket, across said slots, in substantially radial relation to the axis of said crank shaft 17. The trip lever 51 is hung on said fulcrum pin 50 in the slot 48, which is most remote from the axis of said crank shaft, and it is overbalanced by its heavier mass then to the right of and below its ful-

crum and including its arm 52, so that said trip lever is normally presented in the path of said crank "tangent" arm 31, as indicated in Fig. III; although said lever 51 is so proportioned and arranged with reference to its fulcrum that, when free to do so, it gravitates to the position shown in Fig. VI. However, said trip lever 51 is normally upheld by the stop lever 53, then in the prone position shown in Fig. III. Said trip lever is thus normally arranged to be idly tilted by said crank arm 31 at each revolution of said crank shaft 17, from the position shown in Fig. III to the position shown in Fig. IV. The stop lever 53 is hung on the same fulcrum pin 50, in coaxial relation with said trip lever 51, but in the other of said slots, to wit, the slot 47 and, as shown in Figs. III, IV and VII, said stop lever 53 is normally overbalanced by its heavier arm 54, so as to lie upon the top of said bracket 18 out of the path of said crank arm 31. However, said stop lever 53 has the lateral projection 55 extending transversely across the path of said trip lever 51; which thus normally upholds said trip lever 51 in the position shown in Fig. III, against the aforesaid gravitational tendency of said lever 51 to turn to the position shown in Fig. VI; so that said trip lever 51 is enabled to pick up said stop lever 53 when tilted in the reverse direction, as indicated in Fig. V, by reverse rotation of said crank arm 31 incident to the reverse movement of the meter mechanism. When thus set up, as in Fig. V, the arm 54 of said stop lever 53 is not only overbalanced by the mass of said lever 53 to the right of its fulcrum in Fig. VI, but is further rendered temporarily stable in the abnormal position shown in Fig. VI, by the weight of said lever 51 to the right of said fulcrum, which is imposed upon said lever 53 by contact of the arm 52 of said lever 51 with said projection 55 on said lever 53, so that the arm 54 of the latter being thus erected from its normal position shown in Fig. III to the abnormal position shown in Fig. VI is in position to stop the reverse rotation of said crank arm 31 and the meter mechanism connected therewith, after slightly more than two complete reverse revolutions of said crank arm; because said stop lever 53 is then prevented from tilting in the direction of the arrow shown in Fig. VI, by its projection 55 encountering the under part of said bracket 18.

Upon resumption of the normal condition of the meter and consequent rotation of the tangent crank arm 31 in the direction of the arrow marked thereon in Fig. I said stop lever 53 is encountered by the crank arm 31, on the opposite side to that indicated in Fig. VI, and thus returned to its normal position shown in Fig. III. Of course, such reverse movement of the stop lever causes the latter to pick up the trip lever 51 by

engagement of the stop lever projection 55 therewith, to thus restore said trip lever to its normal position shown in Fig. III. In other words; it is characteristic of my stop device that said stop lever and trip lever have freedom of movement with respect to each other to a limited extent, in respectively opposite directions; so that when said trip lever is tilted in the normal direction, it is movable independently of the stop lever but picks up and moves the latter when said trip lever is moved in the reverse direction and, vice versa, said stop lever, when moved to its normal position, picks up said trip lever but, when moved in the opposite direction, is movable independently of said trip lever.

The mechanism above described operates as follows: Said meter being connected by its inlet 2 and outlet 3 with a piping system 20 through which gas is to be dispensed; said mechanism remains stationary until a gas vent is afforded in communication with said outlet 3. Thereupon, the gas flows through the meter and is alternately admitted to and 25 expelled from the two bellows in the respective chambers 4 and 5, with the result that said crank shaft 17 is continuously rotated in the direction of the arrow indicated in Fig. I to operate the registering mechanism 30 by the register shaft 39 and, incidentally, to operate the valve mechanism which controls the passage of gas to and from said bellows chambers 4 and 5 and to and from the interior of the respective bellows in said chambers; the arrangement being such that there 35 is no "dead center", as the mechanism is always adapted to instantly start again upon resumption of the flow of gas through the meter. During such normal operation of the 40 meter mechanism, at each revolution of the crank shaft 17, the trip lever 51 is idly tilted from its normal position shown in Fig. III to the position shown in Fig. IV, without movement of said stop lever 53. However, 45 if there is no flow of gas through the meter, an increase in temperature of the gas in the piping system connected with the meter outlet 3 may increase the pressure of the gas on that side of the meter higher than on the 50 inlet side; with consequent reversal of operation of the bellows and the crank mechanism connected therewith, as above described. However, my stop mechanism permits such 55 reverse movement, without stress upon the meter mechanism, to the extent of more than two revolutions, i. e., from the position of the tangent crank arm 31 shown in Fig. IV to the position of said crank arm shown in Fig. VI; the first reverse revolution merely 60 serving to set up the stop lever to the position shown in Fig. V, in readiness to stop said crank arm 31 when, following the next reverse revolution thereof, it reaches the position shown in Fig. VI.

65 It is characteristic of the form of my in-

vention above described that each of the stop device levers 51 and 53 is heavier at one end than at the other, so that it is maintained in a predetermined position merely by its own weight, unless and until positively moved 70 from that position. Moreover, it may be observed that the stop lever 53 is thus so formed that if the meter be turned up side down to reversely operate its mechanism to reduce the registration, (as may be done with some 75 meters of the prior art); said stop lever 53 automatically gravitates into the position where it is effective to stop such reverse rotation, without regard to the movement of the trip lever 51.

80 It may be observed that each of said levers 51 and 53 may be formed of a sheet metal stamping and, of course, it is immaterial which of them is provided with a transversely extending member to engage the other. 85 The construction and arrangement of said levers so that they may be hung upon a single fulcrum element is advantageous in that a plurality of other parts heretofore considered necessary, are rendered unnecessary, and my device requires less material and is, consequently, not only less costly to manufacture, but easier to assemble, and each of said factors is of considerable commercial 90 importance and value in the quantity production of such meters.

95 Therefore, I do not desire to limit myself to the precise details of construction and arrangement herein set forth, as it is obvious that various modifications may be made 100 therein without departing from the essential features of my invention, as defined in the appended claims.

I claim:

105 1. In a gas meter, the combination with a casing; of a crank shaft in said casing arranged to be operated by a flow of gas through the meter; a crank arm rigidly connected with the top of said crank shaft; a bracket in said casing, having a bearing 110 encircling said crank shaft; said bracket having two slots in it, in parallel relation respectively tangential to circles of different radii and concentric with the axis of said shaft; a single fulcrum pin extending in 115 said bracket across said slots; a trip lever hung on said pin in the slot of said bracket most remote from the axis of said crank shaft, and normally presented in the path of said crank arm, and arranged to be idly 120 tilted by said crank arm at each revolution of said crank shaft in one direction; a stop lever, hung on said fulcrum pin in the other of said slots in coaxial relation with said trip lever and normally out of the path of 125 said crank arm; said stop lever having a lateral projection extending transversely across the path of said trip lever; said trip lever being arranged to be tilted in the reverse direction by reverse rotation of said 130

crank arm incident to the reverse movement of the meter mechanism to then engage said projection on said stop lever and set up the stop lever in position to stop the reverse rotation of said crank arm and the meter mechanism connected therewith, after more than one complete reverse revolution of said crank arm.

2. In a gas meter, the combination with a casing; of a crank shaft in said casing arranged to be operated by a flow of gas through the meter; a crank arm rigidly connected with said crank shaft; a bracket in said casing, having a bearing encircling said crank shaft; said bracket having two slots in it, respectively tangential to circles of different radii and concentric with the axis of said shaft; a single fulcrum pin extending in said bracket across said slots; a trip lever hung on said pin in the slot of said bracket most remote from the axis of said crank shaft, and normally presented in the path of said crank arm, and arranged to be idly tilted by said crank arm at each revolution of said crank shaft, in one direction; a stop lever, hung on said fulcrum pin in the other of said slots in coaxial relation with said trip lever and normally out of the path of said crank arm; said stop lever having a projection extending in the path of said trip lever; said trip lever being arranged to be tilted in the reverse direction by reverse rotation of said crank arm incident to the reverse movement of the meter mechanism to then engage said projection on said stop lever and set up the stop lever in position to stop the reverse rotation of said crank arm and the meter mechanism connected therewith.

3. In a gas meter, the combination with a casing; of a crank shaft in said casing arranged to be operated by a flow of gas through the meter; a crank arm on said crank shaft; a bracket in said casing, having a bearing encircling said crank shaft, a single fulcrum pin in said bracket; a trip lever hung on said pin and normally presented in the path of said crank arm, and arranged to be idly tilted by said crank arm at each revolution of said crank shaft, in one direction; a stop lever, hung on said fulcrum pin in coaxial relation with said trip lever and normally out of the path of said crank arm; said stop lever having a portion extending in the path of said trip lever; said trip lever being arranged to be tilted in the reverse direction by reverse rotation of said crank arm incident to the reverse movement of the meter mechanism to then engage said stop lever and set it in position to stop the reverse rotation of said crank arm and the meter mechanism connected therewith.

4. In a gas meter, the combination with

a casing; of a crank shaft in said casing arranged to be operated by a flow of gas through the meter; an arm on said shaft; a trip lever fulcrumed on an axis transverse to the axis of said shaft and normally presented in the path of said arm, and arranged to be idly tilted by said arm at each revolution of said crank shaft; a stop lever, fulcrumed in coaxial relation with said trip lever and normally out of the path of said crank arm; a single fulcrum member common to both of said levers; means on one of said levers projecting in the path of the other of said levers, whereby movement of said trip lever in one direction may effect movement of said stop lever; said trip lever being constructed and arranged to be tilted in the reverse direction by reverse rotation of said crank arm incident to the reverse movement of the meter mechanism to then engage said projecting means and move the stop lever into position to stop the reverse rotation of said arm and the meter mechanism connected therewith, after more than one complete reverse revolution of said crank arm.

5. In a gas meter, the combination with a casing; of a crank shaft in said casing arranged to be operated by a flow of gas through the meter; an arm on said shaft; a trip lever fulcrumed on an axis transverse to the axis of said shaft and normally presented in the path of said arm, and arranged to be idly tilted by said arm at each revolution of said crank shaft; a stop lever, fulcrumed in coaxial relation with said trip lever and normally out of the path of said crank arm; a single fulcrum member common to both of said levers; means on one of said levers projecting in the path of the other of said levers, whereby movement of said trip lever in one direction may effect movement of said stop lever; said trip lever being constructed and arranged to be tilted in the reverse direction by reverse rotation of said crank arm incident to the reverse movement of the meter mechanism to then engage said projecting means and move the stop lever into position to stop the reverse rotation of said arm and the meter mechanism connected therewith.

6. In a gas meter, the combination with a rotary element arranged to be operated by a flow of gas through the meter; of means arranged to limit reverse rotation of said member, including two levers tiltable in planes tangential to the circular path of said rotary element and having a common fulcrum and so constructed and arranged that one of said levers is always presented in the path of rotation of said member; one of said levers having a portion projecting in the path of the other lever, whereby movement of one of said levers in one direction may

effect movement of the other lever, in the same direction, by engagement of said projecting portion.

7. In a gas meter, the combination with a rotary element arranged to be operated by a flow of gas through the meter; of means arranged to limit reverse rotation of said member, including a trip lever and another lever having a common fulcrum; means on one of said levers projecting in the path of the other of said levers, whereby movement of said trip lever in one direction may effect movement of said stop lever; said levers having freedom of movement in relation to each other in respectively opposite directions; each lever being movable in one direction by said rotary element to pick up the other lever and present it in the path of said rotary element.

8. In a gas meter, the combination with a rotary element arranged to be operated by a flow of gas through the meter; of means arranged to limit reverse rotation of said member, including a trip lever and another lever having a common fulcrum; means on one of said levers projecting in the path of the other of said levers, whereby movement of said trip lever in one direction may effect movement of said stop lever; said levers having freedom of movement in relation to each other in respectively opposite directions; each lever being movable in one direction by said rotary element to pick up the other lever and present it in the path of said rotary element; each of said levers being heavier at one end than at the other; whereby each lever gravitates to a predetermined position when released by the other lever.

9. In a gas meter, the combination with a casing; of a crank shaft in said casing arranged to be operated by a flow of gas through the meter; a crank arm on said crank shaft; a fulcrum pin; a stop lever so fulcrumed on said pin that it is normally overbalanced out of the path of said crank arm, by its own weight; a trip lever so fulcrumed on said pin that it is normally overbalanced, by its own weight, to present it in the path of said crank arm, but free to be idly tilted by said crank arm, at each rotation of the latter in the normal direction; one of said levers having a projection extending in the path of the other of said levers, so constructed and arranged that when the motion of said crank arm is reversed and said trip lever encountered, tilting movement of said trip lever thus effected, sets up the stop lever in abnormal position and stably maintains it in such position to stop the next revolution of said crank arm.

In testimony whereof, I have hereunto signed my name at Erie, Pennsylvania, this 21st day of October, 1924.

WILFORD A. GAUGH.
